[57] **CLAIM**

The ornamental design for a three compartment disposable food serving plate with asymmetric rib geometry, as shown.

DESCRIPTION

FIG. 1 is a view in perspective showing a three compartment disposable food serving plate with asymmetric rib geometry having a design in accordance with the invention; FIG. 2 is a view in elevation of the plate of FIG. 1; FIG. 3 is a top plan view of the plate of FIG. 1; FIG. 4 is a bottom plan view of the plate of FIG. 1; FIG. 5 is a view in elevation and section along line 5—5 of FIG. 3; and, FIG. 6 is a view in elevation and section along line 6—6 of FIG. 3.

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.
